LOUVER TYPE WINDOW

Bernardino Santos, Rio Piedras, P. R.

Application July 29, 1948, Serial No. 41,267

5 Claims. (Cl. 20—62)

1

This invention relates to window structures, and more particularly to louvre type windows capable of being opened and closed to provide ventilation, visibility and light.

The primary object of the invention is to provide a louvre type window having a plurality of panels movable about their longitudinal axis to facilitate easy and rapid opening and closing.

Another object is to provide a louvre type window that does not require any attention in ordinary weather.

Another object is to provide a louvre type window in which the pivoted panel members can be conveniently opened, and locked in a closed position.

Another object is to provide a louvre type window having louvre panels designed such that rain will be excluded when partially opened, and to direct incoming air upwardly and outgoing air downwardly.

Another object resides in the provision of an operator for the louvre panels of the window which is provided with mutually engaging pin and slot locking means to retain the louvre panels in a closed position.

Another object is to provide a louvre type window in which the louvre panels are provided with flanged edge portions which are adapted to interlockingly overlap and form a sealed joint adjacent the meeting edges of adjacent panels.

A further object is to provide a louvre type window that is so simple and rugged in design that it can be manufactured with a minimum of ease and expense.

Other objects and advantages of the invention will become apparent during the course of the following description of the accompanying drawings wherein:

Figure 1 is a front elevational view of the louvre type window showing the panel members in a closed position.

Figure 2 is a vertical cross-sectional view taken on line 2—2 of Figure 1, and looking in the direction of the arrows to illustrate various details of construction and showing the manner in which the edges of the louvre panels are overlapped.

Figure 3 is a rear elevational view of the louvre type window showing the louvre panels in a closed position.

Figure 4 is a horizontal cross sectional view of the window showing the louvre panels in a closed position with the operator in its locked position.

Figure 5 is a horizontal cross sectional view

2

similar to Figure 4, but showing the louvre panels in an open position.

Figure 6 is a vertical cross sectional view taken on line 6—6 of Figure 4 further showing the operator in a latched position.

Figure 7 is a vertical cross sectional view taken on line 7—7 of Figure 4 showing the operator bar, and the mutually engaging pin and L-shaped locking slots for holding the operator and louvre panels in a closed position.

Figure 8 is a vertical cross sectional view taken on line 8—8 of Figure 4 similar to Figure 7, and showing the operator bar in a position of release to permit the operator bar to move relative to the window frame, and

Figure 9 is a vertical cross sectional view similar to Figure 2, but showing the louvre panels in an open position.

In the drawings and more in detail, there is shown for convenience of illustration a window frame structure generally designated 10 for being received in a window opening A of a building construction indicated in dotted lines Figures 2 and 4 through 9. The window frame comprises

25 a pair of vertical side frame members 11 connected at the top and bottom by horizontal frame members 12 and 13 respectively. The side, top and bottom frame members 11, 12 and 13 are provided with integrated trim flanges 14 which are adapted to overlap the edge of the

30 window opening and enhance the appearance of the window structure. The lower frame member 13 is of a sectional shape to provide an inclined sill portion to direct water away from the window sill, and intermediate said inclined portion there is formed a recess 15 for receiving the lower flanged edge of the lowermost louvre panel in a manner presently to be described. The side and top frame rails or members 11 and 12

35 are provided with portions of sectional shape to provide offset portions 16 and 17 respectively to form a recess for receiving the louvre type window structure.

The louvre type window structure includes a 45 pair of vertical side rails 18 of channel section connected at their upper ends in spaced relation by a top rail 19 of angle section. The side rails 18 are seated in the recess formed by the offset portion 16 of the side frame members 11, while

50 the upper rail 19 is seated in the recess formed by the offset portion 17 of the top frame member 12. Suitable fastening elements such as bolts 20 and nuts 21 are provided for securing the vertical rails 18 to the side frame members 11 of the window frame 10, and likewise the top rail

19 can be fastened to the top frame member 12 by similar fastening elements.

Pivoted between the channel rails 18 is a plurality of louvres 22, which may be formed of metal or, if desired, transparent material. Each louvre is provided adjacent its ends with a pivot bracket 23 secured by screws or the like as at 24 along the median line or longitudinal axis of the louvre. Carried by each pivot bracket is a pivot pin 25 which is adapted to extend into one of the flanges 26 of the channel rails 18 and be supported in suitable bearing openings therein. If the louvres 22 are formed of metal, they are bent along their longitudinal edges in opposite directions to form overlapping flanges 27 with adjacent flanged edges. In other words, when the louvres 22 are closed (Figure 2), the longitudinal edges carrying the oppositely directed flanges 27 overlap and form an effective weather seal. If the louvres 22 are formed of transparent panels, rectangular frames may be provided for supporting the panels and the longitudinal edges of the frames may be bent in opposite directions similar to the flanges 27. Thus, it will be seen that the louvres may swing about their horizontal axes between the channel rails 18.

In order to rock the louvres in unison, an operating bar generally designated 28 is arranged at each side of the window. Since both operating bars 28 are identical in construction, a description of one will suffice for both. As best shown in Figure 5, the operating bar 28 is formed of extruded aluminum or other light metal alloy, and consists of a base portion 29 having a pair of spaced apart integrated flanges 30 and 31 for slidably receiving a locking bar 32 therebetween. In addition to the spaced flanges 30 and 31, the inner edge is provided with a flange 33, the edge of which is cut away to provide a series of cut away stepped portions 34 of a shape to conform and receive the end portions of the louvres when the same are in a closed position (Figure 2).

It is to be noted, that the flange 30 of the operating bar 28 projects a slight distance beyond the flange 31 and said flange 30 is provided with a series of longitudinally spaced apart bearing openings (not shown) for receiving pins 35 affixed to the corners of the louvres to project from corresponding end edges thereof. Thus, it will be seen that the louvres are pivotally connected by the operating bar 28 to swing in unison about their longitudinal horizontal pivot axis 25 when the operating bar 28 is moved to and fro.

The sliding latch bar 32 is mounted for sliding movement between the flanges 30 and 31 and is provided with a series of longitudinally spaced slots 36 through which the pins 35 also project. It will be seen, that the sliding latch bar 32 is capable of being moved in a longitudinal direction relative to the operating bar 28 during all positions of movement of said bar.

Also formed in the sliding latch bar 32 and arranged one between each of the longitudinal slots 36 is a series of longitudinally spaced L-shaped slots 38, having entrance portions 39 extending toward one of the longitudinal edges of the sliding latch bar. The L-shaped slots 38 are spaced equal distances corresponding to the spacing of the louvre pivot pins 25 so that when said louvres are swung to a closed position (Figure 2), the projecting ends of the pivot pins 25 will be received in the entrance slots 39 (Figure 8), and then by moving the sliding latch bar 32 upwardly, the pivot pins will be received

in the slots 38. Hence, the sliding latch bar as well as the operating bar will be locked to the projecting ends of the pivot pins 25 and the louvres will be held against rocking movement about their horizontal pivot axis.

An operating lever 40 of U-shaped section has one end extending between the flanges of each channel rail and is pivotally mounted therebetween by means of a pivot pin 41. The sides 42 of the operating lever are spaced as shown in Figures 4 and 5 to straddle the flanges 30 and 31, as well as the sliding latch bar 32 and a pivot pin 44 is passed through suitable bearing openings in the flanges 30 and 31 of the operating bar 28, and through suitable openings in the sides of the operating lever 40. The sliding latch bar has its lower end cut away to slide freely relative to the pivot pin 44. An operating handle 45 is formed integral with one side of each operating lever 40 and said handle extension. The lower portion of the operating bar 28 is cut away slightly to reduce the width of the base portion 29 and allow free swinging to and fro movement about the axis of the pivot pin 44.

An operating crank 47 has its shaft 48 mounted for oscillatory movement in a suitable bearing opening in the flange 30 of the operating bar 28. The shaft portion 48 passes through a slot 49 in the sliding latch bar 32 as shown clearly in Figures 6 to 9 inclusive. The slot 49 extends at right angles at its upper end to provide a horizontal slot 50. A projection 51 is formed integral with the crank 47 and projects into the horizontal slot 50 in the sliding latch bar 32. Hence, when the crank 47 is moved upward and downward by the operating handle 52, the projection 51 swings about an arc as indicated by the dotted lines in Figures 7 to 9 and moves to and fro in the horizontal portion 50 of the slot 49 to raise and lower said sliding latch bar.

In operation, let it be assumed that the pivoted louvres are in their closed and latched position as shown in Figure 2, also that the sliding latch bar 32 is in its raised position (Figure 6) with the pivot pins 25 of the louvres located in the lower portions of the L-shaped slots 38. Now, should it be desired to open the window, the handle 52 is grasped and swung downwardly from the position shown in Figures 6 and 7 to that shown in Figure 8. This motion causes the sliding latch bar 32 to be lowered a corresponding distance so that the pivot pins 25 will register with the entrance portions 39 of the L-shaped slots 38. With the sliding latch bar in its lowered position, the operating lever handle 45 is similarly grasped and moved downwardly from the position shown in Figure 6 to that shown in Figure 9. Thus, the operating bar 28 is moved downwardly and outwardly so that the louvres 22 will be rocked about their longitudinal horizontal axis to the proper angle.

When it is desired to close the window the above operations are reversed. First, the operating lever 45 is moved upwardly which causes an upward and inward movement of the operating bar 28. As this occurs, the louvres 22 are rocked in a reverse direction and the operating bar 28 approaches the channel rails 18. As the operating bar approaches the channel rails 18, the entrance portions of the L-shaped slots are presented to the pivot pins 25 whereby a final movement of the operating lever will cause the pivot pins to be fully seated within the entrance portion of the L-shaped slots. The final locking of the window is accomplished by moving the

operating crank handle 52 in a counter-clockwise direction such that the sliding latch bar will travel inwardly, and thereby cause the pivot pins 25 to be seated in the closed end of the L-shaped slots 38 and effectively locking the pivoted louvres in a closed position with the oppositely flanged longitudinal edges of adjacent louvres in overlapping relationship.

I claim:

1. In a louvre type window, a frame adapted to be mounted in a window opening, a plurality of slats arranged in spaced relation pivotally mounted in said frame, an operating bar normal to the slats and pivotally connected to the end corners thereof, said operating bar being of channel section and formed of extruded metal to provide a pair of spaced ribs, a locking bar slidably mounted between the ribs, a flange on the inner edge of said operating bar, a plurality of stepped portions in said flange that are adapted to receive the end portions of the slats when in closed position and a plurality of L-shaped slots in said locking bar that are adapted to interlockingly engage the pivot pins of the slats and independent means for controlling the operating bar and locking bar.

2. In a louvre type window, a frame adapted to be mounted in a window opening, a plurality of slats pivotally mounted in said frame and arranged in spaced apart relation, an operating bar pivotally connecting each of the slats for pivotal movement about their axis in unison, said operating bar being formed of extruded metal to provide a pair of spaced longitudinal guide ribs, a locking bar slidably mounted between the spaced ribs, a flange on the inner edge of said operating bar, a plurality of stepped portions in said flange that are adapted to receive the end portions of the slats when in closed position and a plurality of L-shaped slots in said locking bar that are adapted to interlockingly engage the pivot pins of the slats, an operating lever for said operating bar and a control crank for said sliding locking bar.

3. In a louvre type window, a frame adapted to be mounted in a window opening, a plurality of slats pivotally mounted in said frame and arranged in spaced apart relation, an operating bar pivotally connecting each of the slats for pivotal movement about their axis in unison, said operating bar being formed of extruded metal to provide a pair of spaced longitudinal guide ribs, a locking bar slidably mounted between the spaced ribs, an operating lever for said operating bar pivotally mounted on said frame and a control crank carried by said operating bar, a bearing opening in said sliding locking bar and said control crank engaging said opening in said sliding locking bar for operating said sliding

locking bar, said sliding locking bar having a series of slots adapted to interlockingly engage the pivots of said slats.

4. In a louvre type window, a rectangular window frame adapted to be mounted in a window opening, a pair of channel bars arranged one at each side of the window and seated in the window frame, a plurality of slats mounted between the channel bars and arranged in spaced relation, pivot pins carried by said slats projecting into said channel bar, an operating bar common to all of said slats, pivoted connections between the slats and operating bar, said operating bar being formed of extruded metal to provide a pair of spaced longitudinal ribs, a locking bar slidably mounted between said ribs, said locking bar being provided with a plurality of L-shaped slots adapted to interlockingly engage the pivot pins of said slats, an operating lever for said operating bar pivotally connected to a channel bar and to the lower end of the operating bar and an operating crank for said locking bar carried by said operating bar.

5. In a louvre type window, a rectangular window frame adapted to be mounted in a window opening, a pair of channel bars arranged one at each side of the window and seated in the window frame, a plurality of slats mounted between the channel bars and arranged in spaced relation, pivot pins carried by said slats projecting into said channel bar, an operating bar common to all of said slats, pivoted connections between the slats and operating bar, said operating bar being formed of extruded metal to provide a pair of spaced longitudinal ribs, a locking bar slidably mounted between said ribs, said locking bar being provided with a plurality of L-shaped slots adapted to interlockingly engage the pivot pins of said slats, an operating lever for said operating bar pivotally connected to a channel bar and to the lower end of the operating bar, and an operating crank for said locking bar carried by said operating bar, said slats being provided with reversely bent longitudinal edges adapted to overlappingly engage the edges of adjacent slats.
